Attest:

UNITED STATES PATENT OFFICE.

JOHN P. ZENNER, OF CHICAGO, ILLINOIS.

STEAM-EXHAUST HEAD.

SPECIFICATION forming part of Letters Patent No. 786,707, dated April 4, 1905.

Application filed November 18, 1904. Serial No. 233,286.

To all whom it may concern:

Be it known that I, JOHN P. ZENNER, a citizen of the United States, and a resident of Chicago, in the county of Cook and State of Illinois, have invented certain new and useful Improvements in Steam-Exhaust Heads, of which the following is a full, clear, and exact description.

My invention relates to steam-exhaust heads; and its object is to prolong the life of the same by adopting a construction that minimizes the rusting and corrosion of the shell at the bottom thereof and particularly in the seams, where, considering the weight of the entire superstructure of the device is sustained thereby, corrosion should be avoided to the utmost extent. This I accomplish by the means hereinafter fully described and as particularly pointed out in the claims.

In the drawings, Figure 1 is a vertical central section of a steam-exhaust head embodying my invention. Fig. 2 is a perspective view of the same. Fig. 3 is a vertical central section of the lower deflector, taken on dotted line 3 3, Fig. 1.

Reference being had to the drawings, A represents the inverted-truncated-cone-shaped lower portion of the sides of my improved steam-exhaust head, and B represents the upper cylindrical portion thereof, whose lower edges are riveted or otherwise secured to the upper edges of said lower portion. The top of this shell A B is closed by a suitable head C, whose outer upwardly-flanged edges are riveted or otherwise suitably secured to the inner circumference of the upper end of part B of the shell and which is concaved and provided with a discharge-opening, which latter has a tapered exit-pipe D, secured to and depending from its edges into the exhaust-head a suitable distance.

The lower edges of the lower portion A of the shell are seated within and secured to the upwardly-flanged edges a of a cast-metal bottom plate E, which latter has an integral central tubular boss F therein, into the shorter downwardly-extending interiorly-screw-threaded portion of which the steam-exhaust pipe G is screwed. The horizontal lower portion of this bottom plate E between the outer

flanges a and the tubular boss F is made quite wide, so as to allow a greater circumference for the attachment of the sheet-metal upper portion of the head. By enlarging this radius of the plate the head itself is held 55 steadier and the liability of the same working loose of its rivets is obviated. The portion of the boss F extending above the bottom plate up into the exhaust-head is longer than the lower portion thereof. At a suitable 60 point at one side of the boss F the bottom plate is provided with a suitable drip-opening and has an integral drip-stub b projecting in a downward and outward direction therefrom, the lower portion of which is interiorly 65 screw-threaded and has a suitable drip-pipe H screwed into its lower end.

Secured to and suspended centrally from the upper portion B of the shell by means of suitable straps c, so that its upper edge is 70 about in the same horizontal plane as the seam uniting the upper and lower portion of the shell, is an inverted-cone-shaped deflector I, the inverted apex of which is above and in alinement with the center of the boss F of 75 the bottom plate E. Adjacent to the inverted apex of this deflector I the sides thereof are provided with two diametrically opposite openings which have secured to and depending down from the edges thereof downwardly and outwardly depending tapered drain-pipes d d, substantially as shown. In view of the seams made necessary at the crotch of the drain-pipes d d and the apex of the deflector I, I prefer to protect the same 80 from the direct action of the exhaust-steam by a protector-plate J, one end of which is secured to the one side of the deflector and then extends down under the apex of the deflector and between the drain-pipes and 85 has its opposite end secured to the opposite side of the deflector. This protector-plate J is useful in preventing the rusting out of the deflector at the crotch of the drain-pipes d d, and thus permitting the leakage from the deflector of the liquids of condensation direct 90 into the mouth of the steam-exhaust pipe. 95

The upper edges e of the deflector I are preferably flanged outward, and within the circumference of these upper flanged edges is 100

a cylindrical baffle-plate or ring K, whose lower edges sit down in the deflector I a short distance and are secured in place by being riveted to the upturned end f of the straps e, substantially as shown. The lower edges of the baffle-plate K are not in contact with the deflector I, but are raised a short distance above the same about the thickness of the straps and the upper edges k of this baffle-plate are preferably slightly curved or flared outward.

In operation the steam expelled from the exhaust-pipe G into the exhaust-head first comes in contact with the protector-plate J, the drain d, and the deflector I and is deprived of a portion of its moisture by the condensation thereof. The steam continuing its upward course is caused to make a downward and outward evolution against the lower side portion of the shell by the flanged edges e of the deflector and then passes up between the said flanged edges and the shell into an annular chamber between said shell and the baffle-plate K. From this chamber the steam passes up over the upper edges of the plate K and downward into the space between it and the exit-pipe D and into the deflector I and then enters the exit-pipe D (which is tapered so as to prevent the back pressure of the steam) and issues into the open atmosphere in a condition in which it will be practically relieved of its moisture and liquids held in suspension which it possessed as it issued from the exhaust-pipe G. This condensation, &c., which took place within the exhaust-head, gravitates down the sides of the shell, through and from the drain-pipes d d, into the bottom plate, and is carried off through the drip-pipe H. The bottom plate E being made of one piece of metal is not affected by the moisture which continually affects the same, which heretofore has caused the bottom of the exhaust-head to corrode at the seams and leak and has greatly reduced the period of usefulness thereof.

What I claim as new is—

1. In a steam-exhaust head, the combination with the exterior shell thereof, and a centrally-perforated top therefor, of an inverted-cone-shaped deflector mounted between said top plate and the bottom of the shell, a floating annular baffle-plate suspended mediate said top plate and deflector, and a cast-metal bottom plate to which the lower edges of the shell are secured having an opening therein for the steam-exhaust pipe and a drip-opening therein between said exhaust-pipe and its outer circumference.
2. In a steam-exhaust head, the combination with the exterior shell thereof, and a centrally-perforated top therefor, of an inverted-cone-shaped deflector mounted between said top plate and the bottom of the shell, a floating annular baffle-plate suspended mediate

said top plate and deflector, and a cast-metal bottom plate having upwardly-projecting circumferential flanges, to which the lower edges of the shell are secured having an opening therein for the steam-exhaust pipe and a drip-opening therein between said exhaust-pipe and its outer circumference.

3. In a steam-exhaust head, the combination with the exterior shell thereof, and a centrally-perforated top therefor, of an inverted-cone-shaped deflector mounted between said top plate and the bottom of the shell, a floating annular baffle-plate suspended mediate said top plate and deflector, and a cast-metal bottom plate to which the lower edges of the shell are secured having a tubular boss in the lower end of which the exhaust-pipe is connected and which extends up into the exhaust-head and a drip-opening therein between said exhaust-pipe and its outer circumference.

4. In a steam-exhaust head, the combination with the exterior shell thereof, and a centrally-perforated top therefor, of an inverted-cone-shaped deflector mounted between said top plate and the bottom of the shell, a floating annular baffle-plate suspended mediate said top plate and deflector, and a cast-metal bottom plate having upwardly-projecting circumferential flanges to which the lower edges of the shell are secured having a tubular boss to the lower end of which the exhaust-pipe is connected and which extends up into the exhaust-head, and a drip-opening therein between said exhaust-pipe and its outer circumference.

5. In a steam-exhaust head, the combination with the exterior shell thereof, and a centrally-perforated top therefor, of an inverted-cone-shaped deflector mounted between said top plate and the bottom of the shell, a floating annular baffle-plate suspended mediate said top plate and deflector, and a cast-metal bottom plate to which the lower edges of the shell are secured having an opening therein for the steam-exhaust pipe and an integral tubular drip-stub between said exhaust-pipe and its outer circumference.

6. In a steam-exhaust head, the combination with the exterior shell thereof, and a centrally-perforated top therefor, of an inverted-cone-shaped deflector mounted between said top plate and the bottom of the shell, a floating annular baffle-plate suspended mediate said top plate and deflector, and a cast-metal bottom plate having upwardly-projecting circumferential flanges, to which the lower edges of the shell are secured having an opening therein for the steam-exhaust pipe and an integral tubular drip-stub between said exhaust-pipe and its outer circumference.

7. In a steam-exhaust head, the combination with the exterior shell thereof, and a centrally-perforated top therefor, of an inverted-

cone-shaped deflector mounted between said top plate and the bottom of the shell, a floating annular baffle-plate suspended mediate said top plate and deflector, and a cast-metal bottom plate to which the lower edges of the shell are secured having a tubular boss in the lower end of which the exhaust-pipe is connected and which extends up into the exhaust-head and an integral tubular drip-stub between said exhaust-pipe and its outer circumference.

8. In a steam-exhaust head, the combination with the exterior shell thereof, and a centrally-perforated top therefor of an inverted-cone-shaped deflector mounted between said top plate and the bottom of the shell, a floating annular baffle-plate suspended mediate said top plate and deflector, and a cast-metal bottom plate having upwardly-projecting circumferential flanges to which the lower edges of the shell are secured having a tubular boss to the lower ends of which the exhaust-pipe is connected and which extends

up into the exhaust-head, and an integral tubular drip-stub between said exhaust-pipe 25 and its outer circumference.

9. In a steam-exhaust head, the combination with a suitable shell, a top therefor having an exit-opening therein, of a steam-exhaust pipe connected with the lower end, and 30 a drip-pipe adjacent thereto, an inverted-cone-shaped deflector suspended centrally above said exhaust-pipe, two drain-pipes projecting downwardly and outwardly from said deflector and a protector-plate in the 35 crotch of said drain-pipes, and a floating annular baffle-plate suspended mediate said deflector and the top of said shell.

In testimony whereof I have hereunto set my hand this 11th day of November, A. D. 40 1904.

JOHN P. ZENNER.
